CLAIM

The ornamental design for a panel, as shown and described.

DESCRIPTION

FIG. 1 is a fragmentary perspective view of a panel showing my new design the pattern is repetitive as shown in FIG. 1 of the drawing;

FIG. 2 is a fragmentary front elevation view thereof, the rear being identical thereto;

FIG. 3 is an enlarged fragmentary cross-sectional view taken along line 3—3 of FIG. 1;

FIG. 4 is a fragmentary bottom plan view thereof;

FIG. 5 is a fragmentary side elevation view thereof, with the opposite side being identical thereto;

FIG. 6 is a fragmentary perspective view of a second embodiment of a panel showing my new design, the pattern is repetitive as shown in FIG. 6 of the drawing; and,

FIG. 7 is an enlarged fragmentary cross-sectional view taken along line 7—7 of FIG. 6.
